UNITED STATES PATENT OFFICE.

JOSEPH JACOBS, OF SAN FRANCISCO, CALIFORNIA.

MAIL-BAG FASTENING.

SPECIFICATION forming part of Letters Patent No. 398,967, dated March 5, 1889.

Application filed October 15, 1888. Serial No. 288,144. (No model.)

To all whom it may concern:

Be it known that I, JOSEPH JACOBS, of the city and county of San Francisco, State of California, have invented an Improvement in 5 Mail-Bag Fastenings; and I hereby declare the following to be a full, clear, and exact description of the same.

My invention relates to the class of fastenings especially adapted for mail-bags; and my 10 invention consists in the constructions and combinations of devices which I shall herein-after fully describe and claim.

The object of my invention is to provide a simple and effective fastening for mail-bags 15 which can be rapidly operated and is not liable to get out of order.

Referring to the accompanying drawings for a more complete explanation of my invention, Figure 1 is an elevation of the front of 20 the bag. Fig. 2 is an elevation of its back on the cross guide-bands D, being broken to show the slot c. Fig. 3 is a horizontal section on the line X X, Fig. 2. Fig. 4 is a vertical cross-section on line Y Y, Fig. 3. Fig. 5 is a perspective view from the front of the bag, the flap a being open. Fig. 6 is a perspective view of the sliding strap C.

A is a mail-bag, the top of which is provided with the usual flap, a, which folds over the 30 top or mouth of the bag. Upon the inner surface of this flap are secured the independent separate tongues B. These tongues are T-shaped, as shown, having a head, b, a shank or stem, b', and a base, b'', which said base is 35 properly secured to or formed with a flange-plate, b³, by which the whole tongue is fastened to the flap.

Through the two folds or sides of the bag, near the top, are made the openings or slits 40 a', through which the tongues B are adapted to pass, so that their heads and shanks project to the back, while their bases fill nicely and snugly said openings or slots, thus practically closing them when the bag is locked 45 and preventing entrance of dust, &c., said bases further acting as guides to immediately and accurately center or place the shanks or stem b' in line with the horizontal leg portions of the slots or grooves of the sliding strap, to 50 be presently described.

On the back of the bag, near the top, is a sliding strap, C, which is held to place and guided by cross-bands D. A short loop or band, E, which is secured to the bag by means of a flanged plate, e, passes through elongated 55 slots e' in one end of the sliding strap, whereby the limits of the movement of the strap are accurately defined, said loop acting in the capacity of a stop.

In the sliding strap C are made T-shaped 60 slots or grooves c, so arranged that the top portion is in a vertical position while the leg portion is in a horizontal position. The vertical portions of the T-shaped slots are so arranged that when the sliding strap is moved 65 in one direction they will come into alignment with the openings or slits a' in the sides of the bag, and when the strap is moved in the other direction said vertical portions will be fully 70 out of line with said slits or openings, which are then crossed by the horizontal portions, while the vertical portions then lie directly under and are covered and protected by the cross-bands D.

Suitable hand-loops, F, may be placed upon 75 the sliding strap in any position adapting it to be readily moved.

The operation of the fastening as far as described is as follows: By moving the sliding strap in one direction the vertical portions of 80 its T-shaped grooves or slots are brought into alignment with the openings or slits a' in the sides of the bag. The flap a is then folded over to place, so that the tongues B, secured to it, pass into the slits or openings in the 85 sides of the bag, their heads and shanks, as heretofore described, passing completely through, while the heads themselves pass through the vertical portions of the grooves or slots in the sliding strap. Said strap is 90 then moved over in the other direction, so as to carry the horizontal portions of its grooves or slots past the shanks or stems of the tongues, so that the heads of said tongues then traverse the horizontal portions of the 95 slots or grooves, and are thereby confined, the vertical portions of said slots or grooves passing under and being protected by the cross guide-bands D. When it is desired to open 100 the bag, the sliding strap is moved in the first

direction, so as to bring the vertical portion of its grooves or slots into alignment with the heads of the tongues, whereupon said tongues may be removed from the strap and taken 5 out of the slits or openings in the sides of the bag, thereby completely freeing the flap *a*; but in order to hold the sliding strap in place when it is engaging the tongues, as heretofore described, I have the following lock: Connected 10 with the flap *a* of the bag in the manner I shall presently describe is a staple, *G*, which is located near one end of the flap and takes the place of a tongue, *B*, at that point. This staple passes through an opening or slit in the sides of 15 the bag, and also through a slot, *c'*, in the sliding strap *C*, which said slot is brought into position to receive the staple when the sliding strap is moved over to lock the tongues, as heretofore described. It then receives 20 the usual post-office lock, *H*, and the fastening is complete. The slot *c'*, which receives the locking-staple, being only of sufficient width to accommodate the staple, will not permit the sliding strap *C* to be moved by 25 bending the bag so long as said staple is in engagement; but, being near one end of the flap *a*, the hand of the operator may be inserted under the end of said flap, so as to withdraw the staple sufficiently to free the 30 strap *C*, whereupon it may be moved to release the tongues *B*. So, too, in fastening, the tongues may be forced to place first and the strap *C* slid over to lock them and to bring its slot *c'* into alignment with staple *G*, which 35 may then be passed through and locked. The lock, being on the back of the bag, is more conveniently located than if it were, as usual, on the front, and there is no need to turn the bag over to lock it. 40 The sliding strap *C*, while it may be made of any suitable or desirable material of a flexible nature, I prefer to make of leather, and I would strengthen and stiffen it by means of the metal strips *c'*, secured to it, and which 45 form protecting-faces for the T-shaped slots or grooves *c*.

The final locking of the bag by means of the staple *G*, I make to serve another purpose, to wit: the connection for the tag or destination-card frame. To the outer surface of 50 the flap *a* are secured the small staples *I*. Upon these is fitted or hinged by one end a flanged plate, *J*, which forms the base-plate of the tag or card frame. Also fitted or 55 hinged to these staples *I* by one end is a hasp-plate, *K*, which forms the top plate of the card or tag frame, said hasp-plate having an open face, *k*, through which the tag or card *L*, which lies between the two plates *J* and *K*, may be 60 seen. Now the locking-staple *G* is secured to the hasp-plate *K* and passes through a slot, *j*, in the end of the plate *J*, and thence through a slot, *a'*, in the flap *a*, and through the sides of the bag and sliding strap *C* to its seat. It 65 will be seen, therefore, that when the bag is locked the tag-frame formed by plates *J* and *K* is also locked; but when the staple *G* is

unlocked in front its plate *K* may be still held in place to confine the tag by means of a short cross-strap and buckle, *M*, on the face 70 of the flap. This short strap need only be loosened when it is desired to change the tag. The mere unlocking of the bag does not affect the tag-frame. When the short strap is relieved, the hasp-plate *K* may be thrown open 75 on its hinged staples *I*, thus uncovering the tag, whereupon another may be inserted. It will thus be seen that the tag or destination-card can be readily inserted in place and is securely held by the same operation which 80 completes the main fastening of the bag. The tag is also in the most convenient place for reference at all times whether the bag be full or whether the flap *a* be turned inside the mouth of the bag when ready to receive mail matter. 85

Having thus described my invention, what I claim as new, and desire to secure by Letters Patent, is—

1. In a mail-bag fastening, the combination of T-shaped tongues on the flap of the bag 90 adapted to pass through openings or slits in its sides or folds, the sliding strap on the back of the bag having the T-shaped grooves or slots for receiving and holding the T-shaped tongues of the flap, and the limiting-stop for 95 defining the movement of the sliding strap, consisting of a loop or band, *E*, secured to the bag and passing through elongated slots *e'* in the strap, substantially as described.

2. In a mail-bag fastening, tongues upon the 100 flap of the bag adapted to pass through its sides or folds, a sliding strap upon the back of the bag and having grooves or slots for receiving and holding the tongues, and a locking-staple passing through the bag and the 105 sliding strap and receiving a lock at the back of the bag, whereby the sliding strap is held, in combination with the frame for receiving the tag or destination-card, consisting of the open-faced plate *K*, hinged to the flap of the 110 bag and carrying the locking-staple, and the flanged plate *J*, secured to the flap and receiving the plate *K* and its staple, substantially as herein described.

3. In a mail-bag fastening, tongues upon the 115 flap of the bag adapted to pass through its sides or folds, a sliding strap upon the back of the bag and having grooves or slots for receiving and holding the tongues, and a locking-staple passing through the bag and the 120 sliding strap and receiving a lock on the back of the bag, whereby the sliding strap is held, in combination with the frame for receiving the tag or destination-card, consisting of the open-faced plate *K*, hinged to the flap of the 125 bag and carrying the locking-staple, and the flanged plate *J*, secured to the flap and receiving the plate *K* and its staple, and the cross-strap and buckle for holding the plates together when the staple is released 130 from the back of the bag, substantially as herein described.

4. In a mail-bag fastening, and in combination with the staple by which the bag is locked,

the frame for the tag or destination-card, consisting of the outer open-faced plate, K, hinged to the flap of the bag and carrying the staple, and the flanged base-plate J, hinged to the flap and having a slotted end through which the staple passes, substantially as herein described.

In witness whereof I have hereunto set my hand.

JOSEPH JACOBS.
